UNITED STATES PATENT OFFICE.

STEPHEN NORTON AND WILLIAM H. RICE, OF ROCHESTER, NEW YORK.

SAFETY-GUARD FOR STREET-CARS.

SPECIFICATION forming part of Letters Patent No. 521,294, dated June 12, 1894.

Application filed September 20, 1893. Serial No. 485,992. (No model.)

To all whom it may concern:

Be it known that we, STEPHEN NORTON and WILLIAM H. RICE, of Rochester, in the county of Monroe and State of New York, have invented a certain new and useful Improvement in Safety-Guards for Street-Cars; and we do hereby declare that the following is a full, clear, and exact description of the same, reference being had to the drawings accompanying this application.

This improvement relates to safety guards carried in front of the street cars for catching and holding any person who may be thrown thereon, and in general features is similar to those embodied in the application of Stephen Norton, filed August 7, 1893, Serial No. 482,625.

The invention consists in the construction and arrangement of parts hereinafter described and embodied in the claims.

In the drawings—Figure 1 is a side elevation of a portion of one end of a street car showing the improvement connected therewith. Fig. 2 is a plan view of the same. Fig. 3 is an enlarged horizontal section of one end 25 of the guard roller and the end of the arm with which it is connected. Fig. 4 is a plan view of one of the guard chains. Fig. 5 is a side elevation of the stay bar.

A indicates a street car, B the truck, and 30 C one of the car wheels.

D is a cross bar forming a buffer attached to the springs a a, and standing across the end of the car. It is padded or covered with some soft material, and serves to break the 35 shock in case a person is thrown upon the guard in front.

E E are two side bars forming the frame of the guard, and carrying at their front ends a roller F. This frame is made in two sections 40 E and E', pivoted at b, so that the outer section carrying the roller can be folded or turned up in front out of the way when the car is out of use. The side bars forming the frame are attached on the under side of the car body by 45 pivots c c which rest in open hooks d d, by which means the frame can turn on the pivots as the car vibrates up and down, and can also be readily attached and removed. Each of these bars is also provided with an offset arm

f, extending under the car, between which 50 arm and the car is interposed a spring g, as shown in Fig. 1. The tendency of this spring is to force the arm downward and to raise the outer end which holds the roller, upward.

G is a stay bar on each side connecting the 55 bar E with the end of the truck B. It is pivoted at i to the bar and at k to the truck, so that it will articulate freely. Preferably the rear portion of the stay bar is cranked upward as shown at l, by which means it is elevated 60 high above the road bed and gives room for snow plows or other devices below.

K is a flexible guard in front, one end attached to the spring buffer D, and the other to the roller F, around which it is wound a 65 partial turn, as shown in Fig. 1. The roller is provided with a spring m, whose tendency is to turn it forward and draw upon the guard, thereby keeping it straight and also producing elasticity when a person is thrown 70 upon the guard so as to depress it. In such case the guard unwinds the roller under the tension. The flexible guard is composed of chains n n, which are attached to the buffer and roller, and a series of cross slats o o bolted 75 thereto as shown in Fig. 4. By being attached at its upper end to the cross bar, higher than the bottom of the car, the guard forms a covering to the bumper which projects from the end of the car, and thus prevents a person 80 from coming in contact therewith in case he is thrown upon the guard.

The operation is as follows: As the car vibrates downward, carrying the guard frame with it, the stay bars G G move also downward 85 at the front end, lengthening the space between the truck and guard frame, and the springs g g pressing on the arms f f turn the guard frame on the pivots c c and elevate the roller F to the same degree that the car is depressed. As the car vibrates upward again the raising of the front end of the stay bars G shortens the space between the guard frame and truck, draws back the guard frame, and depresses the roller F. The roller F therefore 90 retains substantially the same elevation from the track at all times, notwithstanding the vibrations of the car. The springs g g serve 95

an important purpose by taking up all slack and looseness in the turning of the guard frame to compensate for the vibrations.

We do not claim in this application the 5 jointed frame, roller and stays shown in the application of Stephen Norton, filed August 7, 1893, Serial No. 482,625; but,

Having described our invention, what we claim as new, and desire to secure by Letters 10 Patent, is—

1. The combination, with the car and truck, of the guard frame E pivoted to the bottom of the car and provided with the offset arms f f, the springs g g interposed between said offset 15 arms and the bottom of the car, and the stay bars G G pivoted at one end to the guard frame and at the other to the truck, as herein shown and described.

2. The combination of the guard frame composed of two sections pivoted together so that the outer one can be turned up, and provided with pivots at the top, the open hooks with which said pivots connect, the offset arms at 20 the top of the guard frame, the springs interposed between said arms and the bottom 25

of the car, and the pivoted stay bars connecting the guard frame and truck, as and for the purpose specified.

3. The combination of the guard frame pivoted under the car and provided with offset 30 arms, the springs interposed between the arms and the bottom of the car, the stay bars connecting the guard frame with the truck, the spring roller at the front end of the guard frame, and the flexible guard connecting the 35 roller with the end of the car as described.

4. The combination, with a street car, of a flexible guard composed of chains and cross slats attached at the outer end to the supporting frame, and at the inner end to the car 40 above the bumper, and forming a covering to the bumper, as and for the purpose specified.

In witness whereof we have hereunto signed our names in the presence of two subscribing witnesses.

STEPHEN NORTON.
WM. H. RICE.
